UNITED STATES PATENT OFFICE.

EDWARD L. ACKERMAN, OF DETROIT, MICHIGAN, ASSIGNOR TO ACKERMAN-BLAESSER-FEZZY CORPORATION, OF DETROIT, MICHIGAN, A CORPORATION OF MICHIGAN.

SASH-OPERATING MECHANISM.

Application filed April 19, 1923. Serial No. 633,056.

This invention relates to sash operating mechanism and the object of the invention is to provide a sash operating mechanism which will not get out of order and which 5 provides a means for raising or lowering a sash in which the sash is automatically held in position by the operating mechanism at any point in its path of travel. Another object of the invention is to provide a sash 10 operating mechanism by which the window may be drawn to the bottom of the recess provided therefor thus resulting in a saving of space which is very important in present day closed vehicle body construction. A 15 further object of the invention is to provide a sash operating mechanism in which the weight of the sash is counter-balanced to allow a thread of greater pitch to be used in the operating mechanism, thereby providing 20 a sash which may be moved through its path of travel with fewer turns of the operating crank. Another object of the invention is to provide a sash operating mechanism in which the sash is prevented from vibrating 25 within the frame at any adjustment thus eliminating objectionable noises usually caused when the automobile is passing over a rough road. A further object of the invention is to provide a sash operating mechanism 30 in which the sash is supported at two points throughout its path of movement the said points moving upward or downward in a horizontal plane thus preventing the sash from binding in the guideways or frame 35 therefor. These objects and the several novel features of the invention are herein-after more fully described and claimed and the preferred form of construction by which 40 these objects are attained is shown in the accompanying drawings in which—

Fig. 1 is a view of a portion of a closed vehicle body with the upholstery removed to show the sash operating mechanism.

Fig. 2 is a view of the sash operating mechanism when the sash is at its lowermost position.

Fig. 3 is a section taken on line 3—3 of Fig. 1 showing the operating mechanism in the lowermost position.

Fig. 4 is an enlarged detail of the counter-balance spring.

Fig. 5 is an enlarged section taken on line 5—5 of Fig. 1.

As shown in Fig. 1 a framework 1 is provided having guides 2 therein in which a

window 3 is slidably mounted. As shown in Figs. 1, 2 and 3 the window 3 is provided with a sash 4 and secured to the lower edge of the sash 4 as shown more particularly in Fig. 1 is a way 5 which is spaced therefrom. 60 The frame member 1 is provided with a cross support 6 which is secured to the frame member at opposite ends and secured to this support 6 by screw 7 is a plate 8. As shown in Fig. 3 the member 6 is provided with a recess 9 through which a portion of the mechanism extends and the plate 8 at the lower end is provided with a bearing 10 for a screw shaft 11. A collar 12, shown more particularly at the upper end of Fig. 3, is secured 65 to the plate 8 by screws 13 shown more particularly in Fig. 1. A screw 14 is provided in the flange in the collar 12 and extends into an annular groove 15 in the hub of the crank 16 which allows rotation of the crank 70 and prevents removal thereof from the member 12. The crank 16 is provided with a square recess 17 in the hub thereof fitting over a square end 18 of the shaft 19. Secured to the end of the shaft 19 is a bevel gear 22 75 meshing with a bevel gear 23 secured to the upper end of a screw shaft 11 the arrangement being such that rotation of the crank 16 rotates the screw shaft 11. A pair of lazy 80 tongs are provided for raising or lowering the window and consists of a pair of arms 24 and 24^a pivoted at a common center on the bearing 25. Pivoted at the outer ends of the arms 24 and 24^a on the members 26 and 26^a shown in Fig. 4, is a pair of crossed arms 85 27 and 27^a which are pivoted at the point of intersection thereof on a nut 28 which is threaded on the screw shaft 11. The arms 27 and 27^a are provided with outwardly bent 90 ends 29, each end carrying a pin on which a roller 30 is rotatably mounted and extends between the sash 4 and the way 5 as shown in Figs. 1, 2 and 3. These ends 29 are bent so that when the nut 28 is moved to the 95 lowermost position shown in Fig. 2 the pins 30 will move the window and sash to position on the lower cross frame member 1 of the vehicle body. The bearing 25 as shown in Fig. 3 is provided with a recess therein 100 containing a ball 35 on which the lower end of the shaft 11 is rotatably supported. To counter-balance the weight of the sash the pivot pin 26 is secured to the arm 27 and is provided with a slot in the end thereof 105 shown more particularly in Figs. 4 and 5. 110

One end of a flat coiled spring 33 is inserted in the slot in the member 26 and the opposite end thereof engages about a pin 34 provided on the arm 24. The spring 33 is a tempered spring of considerable stiffness and tends to move the joint between the arm 24 and 27 inwardly toward the shaft 11 thus extending the lazy tongs. The pivot pin 26^a on the opposite side of the lazy tongs is secured to the arm 24^a and the arm 27^a is pivoted on this pin. The coiled spring 33^a is secured in the slot provided in the pivot pin 26^a and the opposite end thereof engages about a pin 34^a secured to the arm 27^a. The coiled spring 33^a tends to move the joint between the arms 24^a and 27^a inwardly toward the shaft 11 similar to the action of the spring 33, and both springs operate in conjunction and tend to lift the sash by extending the lazy tongs, the said lifting action being prevented by the position of the nut 28 on the shaft 11 so that the action of the spring tends to counter-balance the weight of the sash and relieves the nut 28 of all strain.

23 The window is shown in the uppermost closed position in Fig. 1 and to lower the window the crank 16 is rotated in a counter-clockwise direction which rotates the shaft 11 and moves the nut 28 downward thereon. 30 This movement of the nut 28 moves the lazy tongs toward the position shown in Fig. 2 and due to the rollers 30 thereon engaging the way 5 the window and sash is lowered into the lower portion of the vehicle body, the window being in the lowermost position when the nut 28 has traveled to the lower end of the shaft 11 as shown in Fig. 2. As the mechanism moves from the position shown in Fig. 1 to that shown in Fig. 2 the 35 springs 33 and 33^a are compressed and counter-balance the weight of the sash during its downward movement. To raise the window the crank 16 is rotated in a clock-wise direction causing the nut 28 to travel up the shaft 11 and the springs 33 tend to expand and assist in the upward movement of the nut 28 and of the window in the sash by counter-balancing the weight of the sash. If the said springs were not used the rotation 40 of the crank to raise the window would be more difficult than lowering the sash as the weight of the sash would retard upward movement of the nut 28 on the shaft 11. By using the springs 33 and 33^a the weight of the sash is counter-balanced and a thread of greater pitch may be used on the shaft 11 as the strain is taken off the shaft thus allowing the window to be raised or lowered with fewer rotations of the crank 16 and 45 shaft 11. As the crank 16 is rotated in a clock-wise direction the lazy tongs are moved from the position shown in Fig. 2 to that shown in Fig. 1 and by means of the rollers 30 move the window up to the closed position as will be readily understood from the

drawing. It is to be noted that with this device the window is solidly supported in position at any point upon cessation of rotation of the crank 16. It is also to be noted that the window is supported throughout its movement at two points one adjacent each vertical edge thereof so that the window is raised or lowered without binding in the frame therefor. When the device has been secured in place, the frame 1 is covered with upholstery cloth up to and over the member 6 so that all the mechanism except the crank 16 and collar 12 is hidden from view.

I have shown and described what I have termed a flat spiral spring, the drawing showing it being formed of a flat strip of metal. It is to be understood, however, that any shape of metal may be used for this spring and, while preferably the spiral is flat in form—that is, all the turns thereof occupying the same general plane, the successive convolutions may be arranged in the form of a cone or other well known type of spiral spring.

From the foregoing description it becomes evident that the device is very simple and efficient in operation, will not easily get out of order, is composed of few parts and is of consequent low manufacturing cost in comparison with other devices of like nature, and provides a device which accomplishes the objects described.

Having thus fully described my invention, its utility and mode of operation, what I claim and desire to secure by Letters Patent of the United States is—

In sash operating mechanism, the combination with a window casing, having side grooves and a sash slidable in the grooves, the lower portion of the window casing being formed to provide a pocket into which the sash may be moved and the pocket being of a depth approximately equal to the length of the sash whereby when the sash when moved into the pocket engages the bottom of the pocket and is practically flush with the opposite end thereof, of operating mechanism for the sash positioned within the pocket comprising a screw shaft extending lengthwise of the pocket, a bearing for the shaft end at the bottom of the pocket, means near the top of the pocket for supporting the opposite end of the shaft, means for rotating the screw shaft, said screw shaft being positioned at one side of the plane of movement of the sash, a lazy tongs comprising a pair of crossed arms and a pair of pivoted arms, said pivoted arms being pivoted to the bearing at the bottom of the pocket, a nut on the shaft to which the crossed arms are both pivoted at the crossing point, the crossed arms at the upper ends being outwardly curved and the said curved ends extending from the pivot point to a greater distance than the opposite ends, said

opposite ends being in pivoted relation respectively with the pivoted arms, a roller mounted at the end of each curved arm, a way in the bottom of the sash into which 5 the rollers project, and counterbalancing springs at the point of connection of the crossed arms with the said pivoted arms, the lazy tongs structure lying between the screen shaft and the plane of movement of the sash,

and the said curved arms of greater length 10 providing a means for moving the sash to the bottom of the pocket with the curved ends of the arms extending over and beyond the folded portions of the lazy tongs.

In testimony whereof, I sign this specification. 15

EDWARD L. ACKERMAN.
